UNITED STATES PATENT OFFICE.

EDWARD J. KRUEGER, OF MILWAUKEE, WISCONSIN.

VENTILATING DEVICE.

Application filed May 14, 1921. Serial No. 469,424.

To all whom it may concern:

Be it known that I, EDWARD J. KRUEGER, a citizen of the United States, and resident of Milwaukee, in the county of Milwaukee, 5 and State of Wisconsin, have invented new and useful Improvements in Ventilating Devices, of which the following is a description, reference being had to the accompanying drawings, which are a part of this specification.

This invention relates to certain new and useful improvements in ventilators and refers more particularly to a device designed for placement at the discharge end of a 15 shaft and operated by the air currents to create a positive suction at the shaft mouth.

It is one of the objects of this invention to provide a device of the class described so designed and constructed as to insure the 20 production of a maximum suction at the air shaft mouth with a minimum amount of air currents for the operation thereof.

The various devices of this character that have heretofore been devised prevent the 25 commercial success thereof due to their excessive cost of production and hence it is another object of my invention to so design and construct the parts thereof as to permit the quantity production thereof with the 30 least amount of expense and workmanship.

It is a further object of the present invention to provide an improved manner of mounting the shaft of a ventilator whereby the same is capable of free rotation and will 35 require the attention of an attendant only at long intervals, the bearings working within cups or containers for the reception of lubricant.

A still further and more specific object 40 of my invention is to provide an improved form of vane for a device of the class described, whereby maximum efficiency is obtainable as well as requiring a minimum amount of work and materials in connection 45 with their production.

With the above and other objects in view which will appear as the description proceeds, my invention resides in the novel construction, combination and arrangement of 50 parts substantially as hereinafter described and more particularly defined by the appended claims, it being understood that such changes in the precise embodiment of the herein disclosed invention may be made as 55 come within the scope of the claims.

In the accompanying drawings, I have

illustrated one complete example of the physical embodiment of my invention constructed according to the best mode I have so far devised for the practical application 60 of the principles thereof, and in which:

Figure 1 is a view part in section and part in elevation illustrating the upper discharge end of an air shaft equipped with my improved device; 65

Figure 2 is an enlarged detailed sectional view illustrating the construction of the form of top bearing I provide for the upper end of the journaled shaft;

Figure 3 is a top fragmentary view taken 70 on the plane of line 3—3 of Figure 1, parts thereof being broken away and in section to more clearly illustrate structural details;

Figure 4 is a fragmentary detailed view taken transversely through Figure 1 on the 75 plane of line 4—4, and

Figure 5 is a fragmentary perspective view illustrating the manner of securing the lower ends of the vanes to the lowermost ring member. 80

It will be readily appreciated by those skilled in the art to which an invention of this character appertains that my device is capable of use in connection with ventilating shafts, chimneys, or any other shafts 85 where it is desired to create a suction or draft therein. In the accompanying drawings a conventional shaft 6 is illustrated in the mouth or discharge end of which a spider bracket member 7 is secured by fastening 90 members 8, which also serve to secure bracket arms 9 to the outer opposite sides of the shaft.

The bracket arms 9 have their outer end portions directed upwardly as at 10 and 95 have secured thereto the lower ends of supporting arms 11, which are preferably formed of flat stock, twisted one half turn to impart added strength thereto and have their upper ends secured to an upper spider 100 bracket 12.

The spider 7 is formed with a centrally bored upstanding projection 13 preferably in axial alinement with an axis of the shaft 6 and has secured therein a cup shaped member 14 which provides the lower ball race for the lower bearing of a shaft 15, the other ball race being formed by an end thrust member 16 mounted on the adjacent shaft end. 105

The bore of projection 13 is enclosed by a cap or cover 17 to prevent grit or other for- 110

esign matter from disturbing the bearing which is provided with lubricant by filling the projection bore. The bearing is adjusted by a set screw 18 which passes through the 5 spider 7 and engages the bearing part 14 as clearly illustrated in figure 1, the set screw being made fast in its position of adjustment by a lock nut 19.

The upper end of the shaft 15 is also provided with a ball bearing positioned within a cup shaped part 20, formed on the spider 12 and into which the shaft 15 extends through an opening 21. The end of the shaft 15 extending into projection 20 is slightly reduced as at 22 and has mounted thereon a hardened collar 23, which with a collar 24 forms a ball race for bearings 25. The collars 23 and 24 are secured together with the bearings 25 therebetween by a ring 26 which has its edges directed inwardly as at 27 to clamp said collars therebetween. The bearing just described is retained within the recess of projection 20 by a sleeve 28, set within the bore thereof and held in engagement with the upper portion of ring 26 by a cover 29 which closes the projection bore. The cover 29 is removably secured in position by fastening 30 and is apertured to receive a plug 31 provided with a channel 32 through which the interior of the projection 20 is supplied with lubricant, the channel 32 being normally closed by a cap 33 which prevents the entrance of foreign matter into the bearing. The lubricant is retained within the projection 20 by a packing ring 34 illustrated in elevation in figure 1, surrounding the shaft and set within a counterbored recess 35 within the bottom thereof.

From the foregoing description it will be readily seen that the shaft 15 is provided with strong bearings capable of adjustment to accommodate for wear and at the same time capable of free rotation with the least amount of friction. The shaft 15 carries a plurality of vanes 36, to be later described, the upper ends of which are supported from a disc member 37 and the lower ends of which are secured to a ring member 38. The disc 37 is centrally apertured and engaged over the reduced threaded end 39 of a collar 40 made fast to the upper portion of shaft 15, the disc being firmly secured in place by a binding nut 41 in threaded engagement with the part 39.

A ring 42 of a diameter equal to the diameter of the disc 37 has lugs or projections 43 secured in spaced relation to the inner periphery thereof and which register with the apertures of the disc 37 and in the upper laterally flanged portion 44 of a cone member 45 to receive fastening bolts 46. The lower end of the cone member 45 is made fast to the shaft at a point near its center by a collar 47. The member 45 braces the

vane structure and by reason of its shape prevents the formation of air pockets and eddying currents in the space between the vanes. It will be noted that the collars 40 and 47 adjustably support the conical member 45, and the vanes fastened to the ring carried by the disc 37 as an entirety, on the shaft 15, thus permitting ready adjustment of the device in assembling. Variations in the distance from the top of the air shaft 6 to the bracket member 7 are also taken care of by this adjustable feature.

The lower ring 38 surrounds the mouth of the shaft 6 with its uppermost edge positioned thereabove and its lowermost edge therebelow, and the same is retained concentric with the air shaft mouth, by spokes 48 having their outer ends made fast to the ring 38 and their inner ends secured to a washer or plate 49. Each vane 36 is formed from a length of metal, one longitudinal edge of which is curled about a reinforcing wire 50 as at 51, whereby a gutter is provided for directing moisture which may gather thereon downwardly below the air shaft mouth. Each vane is centrally longitudinally ribbed as at 52 and has its upper end spot-welded to the outer face of ring 42 and its lower end spot-welded at one corner 53 to the ring 38, the other corner 54 being struck outwardly and apertured to receive a reinforcing wire 55.

The vanes are medially braced by a reinforcing wire 56 passed therethrough whereby an additional factor of safety is obtained. From experience I have found that maximum efficiency is obtained by having the upper portion of the vane curved and the lower end formed on a straight line inclined downwardly and inwardly with respect to the axis of the shaft 15. The upper ends of the vanes are preferably overlapped whereby the elements are restrained from entering the mouth of the shaft as will be readily obvious.

From the foregoing description taken in connection with the accompanying drawings, it will be readily obvious to those skilled in the art, to which an invention of this character appertains, that I provide a ventilating device which will be capable of adaptation to ventilating shafts of all sizes and kinds, and which will operate in a highly satisfactory manner and require a small amount of attention on the part of an attendant.

What I claim as my invention is:

1. In a device of the class described, a journaled shaft, a disc member adjustably secured to the upper portion of said shaft and having spaced openings therein near its periphery, a ring, apertured lugs on the inner periphery of the ring in register with the openings of said disc member, a cone member having its lower end adjustably se-

cured to said shaft and its upper end struck laterally and having openings therein registering with the openings of said disc member and ring lugs, fastening means engageable in the registered openings, and vanes suspended from said ring.

2. In a device of the class described, a bearing unit comprising a bracket having a counter-bored projection, a rod projectable in said bore, a sleeve engageable over said rod part in said bore, a ring of substantially right-angular shape in transverse section, ball bearings confined between said sleeve and ring, a collar member disposed in said bore and engaging the bearing formed by said sleeve and ring, a cover for said bore and engaging said collar member to retain the same in engagement with the bearing, said projection having a counter bored recess at the point of entrance thereto of said rod, means permitting the supplying of lubricant to said bore, and a felt washer in said recess and surrounding the rod to prevent leakage of lubricant out of said recess.
- 25 3. In a device of the class described, comprising an air shaft, a bracket positioned above the mouth of said shaft and having a recess therein in axial alinement with the shaft, a spider member secured to the air

shaft and having a bearing recess therein in 30 axial alinement with the recess in said bracket, a shaft journaled in the recesses of the bracket and spider members, a collar secured to the journaled shaft adjacent the upper end thereof, a reduced and threaded 35 portion on the upper end of said collar, a centrally bored disc having a plurality of apertures around its periphery, said disc being positioned on said collar with the threaded top portion thereof extending 40 through the central bore of the disc, a binding nut threaded on said collar threaded portion and adapted to secure the disc member on said collar, a sleeve ring, apertured lugs on the inner periphery of the ring in 45 register with the apertures of said disc, an inverted cone member having its base flanged laterally and apertured in alinement with the apertures of the disc and lugs, means binding the disc, ring and cone member through said apertures, a second collar secured to said journaled shaft having the upper portion of its bore flared to receive and firmly secure the apex of said cone member, and vanes carried by said ring. 55

In testimony whereof, I affix my signature.

EDWARD J. KRUEGER.
